MILITARY CAP

Percy Merton, Hillsdale, N. J.

Application March 22, 1944, Serial No. 527,632

4 Claims. (Cl. 2—195)

This invention relates to headgear of the type worn by persons in uniform, and more particularly relates to a cap which may be worn advantageously by personnel in the military service.

Heretofore a cap of the type mentioned has been found unsatisfactory because of the use of certain materials in such manner the cap cannot be blocked to a correct head size, which makes for oversize and bulky or padded appearance. Also, the cap does not fit against the head properly with the desired ease and comfort. Due to the extra materials used costs both as regards material and labor involved in the production on a quantity basis are unnecessarily great.

An object of the present invention is to overcome the above mentioned drawbacks and disadvantages.

A further object is the provision of a cap of the type having a visor which will be soft and comfortable with a front designed to retain its shape while other aspects of the cap render it smart in appearance with the full benefit of being light in weight, cooler and possessing a better wearing quality.

A further object is the provision in a cap of the indicated character of a detachable reinforcement or stiffener for the front and crown flare and which also serves as a support for an insignia device and a holder for identification means which will be protected and always in view inside the cap for identification purpose.

A further object of the invention is the provision of a cap having the aforesaid features to the end that the cap will be flexible so as to be head-conforming, and which may be collapsed or folded so as to be convertible to service and traveling conditions.

With the foregoing, other objects of the invention will appear when the following specification is read in conjunction with the accompanying drawing, in which—

Fig. 1 is a central vertical sectional view of a cap embodying the features of the invention.

Fig. 2 is a fragmentary vertical sectional view showing parts of the cap separated.

Fig. 3 is an enlarged detail sectional view taken on the line 3—3 of Fig. 1.

Fig. 4 is side view of a combined tip stiffener and identification card holder.

Fig. 5 is a sectional view taken on the line 5—5 of Fig. 4.

Fig. 6 is a perspective view of the finished cap.

In accordance with the invention, the cap has a felt or fabric structure 10 consisting of a body

or head-encircling section 11 and a crown or top section 12. The structure 10 may be made of one piece of material, such as felt or fabric. In the present instance, the structure 10 of one piece has a seam 13 formed as a line of demarcation between the portion 11 and the crown 12. If desired, however, the structure may be made of two or even three pieces. The crown 12 is flat but flares upwardly from the seam 13 and the flared portion of the crown is somewhat higher at the front than at the rear to provide a tip 14.

The body or head-encircling section 11 has an inturned edge portion 15 on the inside thereof extending entirely around the section 11. A sweatband 16 of any suitable type is secured to the edge portion 15. If desired, a full lining may be incorporated in the cap or merely a lining strip 17 extending from the front to the back of the crown section to the seam 13, as shown in the present instance. The inside of the body or head-encircling section is devoid of any stiffening and supporting materials, such as rattan, canvas, buckram and the like. This enables the attainment of a perfect and correct head size of the body section of the cap which is head-conforming and in proportion to the features of the face of the wearer so that the cap will not appear oversize and bulky or padded.

A visor or peak 18 of leather or other material or combination of materials has a fabric strip 19 bent longitudinally upon itself at the upper edge. A semi-rigid or flexible stiffener 20 has its lower edge arranged between the folds of the strip 19. The strip 19 is arranged on the outside of the upper edge portion of the visor 18 and stitching 21 runs through the visor, strip and stiffener to secure the stiffener to the visor so that the latter two parts are disposed at an obtuse angle with respect to each other, as shown most clearly in Fig. 2. The section 11 is secured or stitched to the visor 18. The stiffener 20 may be made of buckram or any other equivalent material having the required stiffness, yet flexible circumferentially. The stiffener 20 has a central portion 22 which is higher than each of the like side portions 23. The central portion 22 projects upwardly approximately to the seam 13 or the juncture of the head-encircling section 11 with the crown 12. Each of the side portions 23 has a hole 24 near the end thereof. The visor 18 is thicker than the stiffener 20, the latter consisting of a single ply. Thus, the visor has the required strength and stiffness while the stiffener 20 is more flexible for the intended purpose.

In accordance with the invention, a flexible

band 25 which serves as a reinforcement is arranged to encircle the head-encircling section 11 on the outside thereof. The band 25 may be made of canvas or analogous material. Surrounding the band 25 is another band 26 of braid which serves as trimming. The bands 25 and 26 are stitched along the edges thereof to the section 11. These bands 25 and 26 overlie the stiffener 20 and completely conceal the same. Button ornaments 27 and a strap 28 are applied to the cap. The buttons are at the sides, respectively, on the outside of the strap 28 which in turn is on the outside of the band or braid 26. Wires on the back of each button extend through the strap 28, bands 25 and 26, the related hole 24 and the section 11, the inner ends of the wires being bent laterally to retain the button in place.

In accordance with another feature of the invention, use is made of a device 29 which serves as an identification holder or container and a reinforcement to shape the crown at the front with the desired flare and to support a shield, emblem or insignia 30. The device 29 is made of semi-rigid material, such as Viscoloid, Celluloid, acetate, and the like. The device consists of two parts cemented or otherwise secured to each other to provide a pocket to receive an identification card 3 containing the name and address of the owner. One or both parts may be transparent so that the card will be readily visible and the contents thereof readable at a glance.

The device 29 is arranged on the inside of the crown section and its lower edge is in proximity to the seam 13 to receive support so that the device will be substantially erect. The crown section 12 has an eyelet 31 and the device has a hole 32 therein for registry with the eyelet. The shield 30 has a screw 33 on the back which carries a nut 34. The shield is arranged outside of the crown section 12 and its screw 33 extends through the eyelet 31 and the hole 32 in the device on the inside of the section 12. The nut screwed home clamps the shield 30 and the device 29 in place. These parts may be readily detached and

the crown collapsed without interference of the stiffener 20 so that the cap may be put into a traveling bag or box to occupy a minimum of space.

5 I claim:

1. In a military cap, a felt or fabric body having a crown and a head-encircling portion, a visor having an upstanding stiffener conforming to the curvature of the visor at the top, said stiffener arranged on the outside of said head-encircling portion and projecting upwardly approximately to the juncture of said portion with the crown, a reinforcing band surrounding the head-encircling portion and overlying said stiffener, and means securing the visor and its stiffener to said head-encircling portion.

2. In a military cap, a felt or fabric body having a crown and a head-encircling portion, a visor having a curved semi-flexible stiffener consisting of an upstanding front central portion and side portions in continuation of the central portion, said stiffener arranged on the outside of said head-encircling portion and the central portion projecting upwardly approximately to the juncture of the head-encircling portion with the crown, said stiffener serving to shape the front of the head-encircling portion and to provide added support for ornaments of the cap.

3. In a military cap, a felt or fabric body having a head-encircling section, a semi-flexible stiffener of stiffened woven material on the outside of said section and overlying the front and parts of the opposite sides only, a fabric binding secured to the lower edge of the stiffener, a visor secured to said binding, and the visor secured to said head-encircling section.

4. In a cap having a head-encircling section, a visor, a stiffener attached to the upper edge portion of the visor, the stiffener being disposed on the outside of the head-encircling section and projecting upwardly approximately to the upper line of said section, and the said edge portion being attached to said head-encircling section.

45 PERCY MERTON.
